UNITED STATES PATENT OFFICE.

WILLIAM R. SCHREMP, OF NEW YORK, N. Y., ASSIGNOR TO UNION MILLS, INC., OF HUDSON, NEW YORK.

UNDERGARMENT.

1,143,444.

Specification of Letters Patent.

Patented June 15, 1915.

Application filed January 30, 1914. Serial No. 815,407.

To all whom it may concern:

Be it known that I, WILLIAM R. SCHREMP, a citizen of the United States, and a resident of the city of New York, Manhattan Beach, borough of Brooklyn, in the county of Kings and State of New York, have invented a new and Improved Undergarment, of which the following is a full, clear, and exact description.

10 The invention relates to knit undershirts and union suits, and its object is to provide a new and improved undergarment arranged to provide elasticity in an up and down direction at the neck and both in the front 15 and back or at the back only, thus insuring a perfect fit of the garment on the body of the wearer and allowing a very desirable freedom and stretching of the garment in a vertical direction to accommodate the motions of the body of the wearer without 20 danger of binding especially at the neck.

In order to accomplish the desired result use is made of a yoke of an elastic ribbed knit fabric, inserted in the body of the garment and having its wales extending horizontally approximately at right angles to the wales of the body of the garment, thus allowing the yoke to stretch in an up and down direction.

30 A practical embodiment of the invention is represented in the accompanying drawings forming a part of this specification, in which similar characters of reference indicate corresponding parts in all the views.

35 Figure 1 is a front elevation of the garment; Fig. 2 is a rear elevation of the same; Fig. 3 is a front elevation of a modified form of the garment showing the yoke extending along the back and the shoulders 40 only; Fig. 4 is a plan view of the yoke illustrated in Figs. 1 and 2.

The union suit illustrated in Figs. 1 and 2 consists of the body A, integral legs B and arms C sewed to the body A in the usual manner. The body A is made of an elastic ribbed knit fabric having its wales extending in a vertical direction, and the body is provided at the front median line with the usual closing flaps D provided with fastening devices E, such as buttons and button-holes, for fastening the flaps together. The body A is provided with an inserted yoke F made of an elastic ribbed knit fabric, the wales of which run in a horizontal direction,

that is, approximately at right angles to the 55 wales of the body A. As shown in Figs. 1 and 2, the yoke F has its rear edge approximately straight and extending from one sleeve seam to the other, and the yoke extends over the shoulders to the front of the 60 garment with the front edge of the yoke approximately extending from the flaps D to the arm seams. The yoke F is provided with a neckband G joined at the front to the overlapping closing flaps D. It will 65 be noticed that by constructing a yoke in the manner described, elasticity in an up and down direction is provided in contrast to the exceedingly limited up and down elasticity of the body A, the wales of which 70 run in a vertical direction and thus prevent stretching in an up and down direction but allowing stretching of the body in a sidewise direction.

In the modified form shown in Fig. 3 75 the body A' is similar to the body A and is provided with overlapping closing flaps D' and fastening devices E' as well as with arms C'. The yoke F' in this case extends across the back the same as the yoke F previously mentioned, but this yoke F' after passing over the shoulders does not extend further down at the front of the body A'. It will be noticed that in this case the neckband G' is partly attached to the yoke F' 80 and partly to the body A' and terminates at the front in the overlapping closing flaps D'. It will also be noticed that in this construction, the desired up and down elasticity is provided at the back and at the shoulders 85 but none at the front of the body A', as above described in reference to Figs. 1 and 2.

It is understood that the yokes F and F' although shown in connection with union suits can be readily used on undershirts only, 95 if desired.

The yoke construction above described is preferably provided in a union suit such as shown in Figs. 1 and 2, having a flexible crotch construction including crotch flaps H 100 and H', and the body A is for this purpose provided with a crotch opening which extends at the back of the body A at the waist line in a desired direction, and under the crotch a distance to the front thereof, that 105 is, to the lower end of the overlapping closing flaps D. This opening in the body A is closed by the crotch flaps H and H', of

which the under crotch flap H is secured along the right-hand side edge by stitches I to the corresponding side of the crotch opening, and the outer flap H' is secured at its 5 left side edge by stitches I' to the left side edge of the crotch opening, so that the flaps readily overlie one the other and can be opened up by moving the same in opposite directions, as plainly indicated in Fig. 4. 10 The back and front ends of the overlying flaps H and H' are secured by stitches I², I³ (see Figs. 2 and 1) to the body A. The flap H is adapted to be fastened at its free or unattached right-hand edge to the under- 15 lying flap H by the use of a fastening device J, such as buttons and buttonholes, to securely hold the outer flap H' in closed position. The flaps H and H' are tapering from the upper edge of the back downward 20 to the crotch, and then taper upward at the front, as plainly indicated in Figs. 1 and 2. The crotch flaps H and H' are made of elastic ribbed knit fabrics having the wales running in a horizontal direction, so that 25 the flaps are free to stretch in an up and down direction, thus giving the desired free-

dom to the wearer's body especially to the upper portion of the lower limbs.

By arranging a garment in the manner described a maximum stretching in a vertical direction of about seven inches is obtained, that is, about five inches at the back and two inches at the front, thus insuring a perfect fit of the garment and allowing a very desirable freedom without danger 35 of undue binding when bending the body or the limbs.

Having thus described my invention, I claim as new and desire to secure by Let- 40 ters Patent:

A knitted garment, comprising a body provided with vertical wales and having an inserted single piece, seamless yoke, provided with a neck-band and with wales which ex- 45 tend horizontally.

In testimony whereof I have signed my name to this specification in the presence of two subscribing witnesses.

WILLIAM R. SCHREMP.
